UNITED STATES PATENT OFFICE.

EDWARD H. PRIEBE, OF DETROIT, MICHIGAN, ASSIGNOR TO GENERAL MOTORS CORPORATION, OF DETROIT, MICHIGAN, A CORPORATION OF DELAWARE.

AUTOMOBILE VENTILATOR.

Application filed September 8, 1924. Serial No. 736,569.

This invention relates to ventilators, and is illustrated as embodied in a cowl ventilator for a Cadillac automobile. An object of the invention is to provide means operated by the ventilator handle for holding the ventilator in any desired position. In one desirable arrangement, swinging the handle in either direction first disengages a holding pawl and then moves the ventilator. 10 Various features of the invention, and the advantages of the described construction, will be apparent from the following description of one illustrative embodiment shown in the accompanying drawings, in which:

Figure 1 is a vertical longitudinal section through a part of the cowl and through the cowl ventilator;

Figure 2 is a transverse section on the line 2—2 of Figure 1; and

Figure 3 is a vertical section on the line 3—3 of Figure 2, showing the ventilator in side elevation.

In the arrangement shown, the cowl 10 is formed with a channel 12 surrounding the ventilator opening closed by the top 14 of the ventilator. The top 14 is carried by a pressed metal part 16 across the back of which is a bar 18 secured to, or integral with, arms 20 at its ends. Arms 20 are pivoted at 22 on stationary supports 24 secured by bolts or screws 26 to the bottom of the side portions of channel 12. Only one of the arms 20 and one of the supports 24 appear in the drawings. Except as further described below, these parts may be of any desired construction.

The one of the supports 24 which appears in the drawings is provided with a ratchet part 28, any tooth of which may be engaged by the end 30 of a pawl or plunger 32. Pawl 32 is guided by end 30 sliding in a slot in arm 20, and by a stud 34 carried by arm 20 and passing through a slot 36 in the pawl. The pawl is urged toward the ratchet by a leaf spring 38 engaging pins 40 on arm 20.

The ventilator is operated by a handle 42 pivoted on stud 34, which engages, after a certain amount of lost motion, one or the other of two spaced lugs 44 bent inwardly from arm 20 on opposite sides of arm 42. During this lost motion, pawl 32 is with-

drawn against the resistance of spring 38 by engagement of one or the other of two 55 cam shoulders 46 with one of two shoulders 48 formed on the pawl. For convenience of manufacture, shoulders 46 (also shoulders 48) are made as a continuous ledge extending clear across handle 42 (or 60 pawl 32). The ledge forming shoulders 48 (or 46) may, if desired, be a separate part having a shank set into an opening in the pawl (or handle) proper.

It will be seen that rocking handle 42 65 in either direction first disengages the pawl, and then swings the ventilator. On the release of the handle, spring 38 causes the pawl to reengage the ratchet.

While one illustrative embodiment of my 70 invention has been described in detail, it is not my intention to limit its scope to that particular embodiment, or otherwise than by the terms of the appended claims.

I claim:

1. A cowl ventilator for an automobile comprising a cowl having an opening therein, a ventilating closure for said opening, a support secured to the under side of said cowl adjacent the opening, a swinging member rigidly secured to the ventilating closure and pivoted to said support, a pawl movably mounted on said swinging member and yieldingly engaging the ratchet, and an operating handle effective to first withdraw the pawl 75 from the ratchet and then to close the ventilating closure.

2. A cowl ventilator comprising a cowl having an opening therein, a ventilating closure for said opening, a support secured to the under side of said cowl adjacent the opening, a swinging member rigidly secured to the ventilating closure and pivoted to said support, a ratchet on said support, a pawl 90 movably mounted on said swinging member and yieldingly engaging the ratchet, an operating handle pivoted on said swinging member, means by which the rotation of the handle first releases the pawl 95 and thereafter rotates the swinging member and the ventilating closure.

In testimony whereof I affix my signature.

EDWARD H. PRIEBE.
